UNITED STATES PATENT OFFICE

ERNST BURMESTER, OF BURG, NEAR BREMEN, AND HERMANN HEIN, OF BREMEN, GERMANY, ASSIGNORS TO YACHT- UND BOOTSWERFT BURMESTER M. B. H., OF BURG, NEAR BREMEN, GERMANY, A CORPORATION OF GERMANY

BOAT

Application filed November 26, 1928, Serial No. 322,020, and in Germany March 6, 1928.

The present invention relates to boats, especially to lifeboats, and an object of this invention is to provide a new method of constructing boats. Another object of this invention is to increase the air content of the boat and thereby the floating properties of the same by suitably constructing and arranging the seats.

According to this invention a boat is provided with transverse seats which consist of hollow fluid tight chambers filled with air or other gas. The seats thus formed are preferably stepped and extend to the bottom of the boat. The provision of such seats transversely arranged with respect to the length of the boat imparts to the latter a satisfactory transverse rigidity as such seats take the place of the usual special stiffening means. These hollow members also obviate all necessity for the usual air chambers disposed along the sides of the boat. The proper maintenance of the air chambers, which are of course large according to this method of construction is easier than that of the small air chambers provided by other constructions. Moreover the construction of the seats themselves as air chambers leaves the space free in the boat which would otherwise be taken up by the air chambers. The hollow transverse chambers may be divided by partitions so that if a leak occurs only a part of the chamber is filled.

The accompanying drawings show diagrammatically an example of construction according to the invention in longitudinal section in Figure 1 and in plan in Figure 2. Similar views of a modified construction are shown in Figures 3 and 4.

The boat is provided with hollow fluid tight chambers *a* filled with air or other gas which are arranged transversely with respect to the length of the boat and are attached to the outer shell of the same. The number of the chambers *a* is chosen to suit the length of the boat. The chambers *a* are stepped to form transverse seats. They are further provided with channels *b* for conveying water which may accumulate between them. Each chamber has at least one access opening or

man hole *c* through which its inside is accessible.

The chambers can also be divided by partitions *d* transversely to their length, as shown in Figure 2, so that if a leak occurs these partitions prevent the whole of the chamber being filled. In this case each division of the hollow member is provided with an access opening or man hole.

In the construction shown in Figures 3 and 4 closing means *e*, which may consist of any known suitable obturator, are constructed in each of the channels and may be operated from outside. Each individual channel *b* can be closed by these closing means so that the flow of water through the spaces *a* and *f* can be interrupted at any desired place. For instance if a leak occurs in one of the intermediate spaces *f* between the seats the adjacent channels *b* can be closed and thus the in-flow of water is restricted to this intermediate space only. Again, the inflowing water can be led off in a certain direction only by closing only one of the adjacent channels and in this way led, for example to a pump.

In the drawings, for the sake of example, two closable channels for each hollow member are shown. One of these channels generally serves as a reserve channel. More than two channels can however be provided for each hollow member and they can be used to regulate the flow of water through the boat in accordance with the water accumulated in the individual intermediate spaces. Thus the water can be distributed to keep the boat level or the water accumulated more at one place can be fed quicker in one direction. The same object can be attained by suitably adjusting the closing means.

We claim:

1. A boat comprising a plurality of double-sided and stepped transverse seats arranged in the boat, each seat provided with a channel running therethrough, said seats consisting of hollow gas-filled fluid tight chambers.

2. A boat comprising a plurality of double-sided and stepped transverse seats arranged in the boat, each seat provided with a channel running therethrough, said seats consisting

of hollow gas-filled fluid tight chambers, and closing means for said channels.

3. A boat comprising a plurality of double-sided and stepped transverse seats arranged in the boat, each seat provided with a channel running therethrough, said seats consisting of hollow gasfilled fluid tight chambers, closing means for said channels, and independent actuating means for each 10 set of said closing means.

4. A boat comprising a plurality of double-sided and stepped transverse seats, each having at least one transverse channel therein, said seats consisting of hollow gas-filled fluid tight chambers.

5. A boat comprising a plurality of double-sided and stepped transverse seats each consisting of a hollow fluid tight chamber extending to the bottom of the boat, said 20 seats having two openings therein and being traversed by channels, and a transverse partition in each of said chambers arranged between the openings.

6. A boat comprising a plurality of double-sided and stepped transverse seats arranged in the boat, each seat provided with a channel running therethrough, said seats consisting of hollow gas-filled fluid tight chambers, and closing means for said channels and actuating means therefor disposed in spaced relation from said closing means.

7. A boat comprising a plurality of double-sided and stepped transverse seats consisting of hollow fluid tight air chambers 35 having access openings therein and traversed by channels, a transverse partition in each air chamber, an obturator in each channel, and a set of closing means for each obturator.

40 In testimony whereof we affix our signatures.

ERNST BURMESTER.
HERMANN HEIN.
